(57) **ABSTRACT**

Disclosed are pour point depressants used in compositions and methods for achieving the cold flow properties of synthetic feedstock derived from plastic. A method of obtaining the synthetic feedstock is also disclosed, which includes heating plastic under substantially oxygen free conditions at a temperature of from about 400° C. to about 850° C. to produce a pyrolysis effluent, condensing the heated a pyrolysis effluent to obtain a synthetic feedstock, recovering the synthetic feedstock, and adding a pour point depressant to the synthetic feedstock to lower the pour point.

**COLD FLOW ADDITIVES FOR
PLASTIC-DERIVED SYNTHETIC
FEEDSTOCK**

**CROSS REFERENCE TO RELATED
APPLICATIONS**

This application claims the benefit of U.S. Provisional Patent Application Ser. No. 63/078,111, filed Sep. 14, 2020, and is a divisional of U.S. patent application Ser. No. 17/471,784, filed Sep. 10, 2021, the disclosures of which are incorporated by reference into the present application.

FIELD OF APPLICATION

The application is directed at improving the cold flow properties of synthetic feedstock from plastics.

BACKGROUND

Plastic is the fastest growing waste product and poses a significant environmental problem. Converting waste plastic into useful, higher value products such as crude oil or feedstock for the production of olefins in a steam cracker provides an opportunity to deal with the plastic waste problem.

Plastic is primarily made up of polyethylene and polypropylene. Through various processes such as pyrolysis, the carbon-carbon bonds and carbon-hydrogen bonds of the plastics are broken into shorter (oligomeric) chains. The resultant products from such processes can contain varying amounts of the oligomeric chains from the breakdown of the plastic that can be conformationally similar to wax molecules, such as paraffin and olefins.

The presence of these wax-like structures can result in solidifying or precipitating when the temperature drops, for example below 0° C. As additional wax precipitates, the crystals grow and, finally, if the temperature is decreased far enough, the crystals will grow together to form a three-dimensional network that immobilizes the fuel or oil. This solidification process is sometimes referred to as gelation. The precipitation of the wax can cause problems during the recovery, transport, storage or use of the synthetic feedstocks. The precipitated wax-like materials can block filters, pumps, pipelines, and other installations or be deposited in tanks, thus entailing additional cleaning.

Hence, additives that can depress or lower the pour points to maintain the fluidity of the synthetic feedstocks (e.g., fuel or oil) at lower temperatures are desired.

SUMMARY

Described herein are compositions and methods for improving the cold flow properties such as reducing or lowering the pour points of synthetic feedstocks from plastics.

In one aspect is a method of improving the cold flow properties of a plastic-derived synthetic feedstock composition comprising:

adding a pour point depressant to a plastic-derived synthetic feedstock composition.

In another aspect is a method of obtaining the synthetic feedstock comprising:

(a) heating plastic under substantially oxygen free conditions at a temperature of from about 400° C. to about 850° C. to produce a pyrolysis effluent;

2

(b) condensing the heated a pyrolysis effluent to obtain a synthetic feedstock; (c) recovering synthetic feedstock; and

(d) adding a pour point depressant to the synthetic feedstock to lower the pour point.

In another aspect is a composition comprising a synthetic feedstock derived from plastic and a pour point depressant.

In yet another aspect is a composition comprising a pour point depressant and a synthetic feedstock, wherein the pour point depressant is a polymer added to the synthetic feedstock, the synthetic feedstock is provided by the method comprising:

(a) heating plastic under substantially oxygen free conditions at a temperature of from about 400° C. to about 850° C. to produce a pyrolysis effluent;

(b) condensing the heated a pyrolysis effluent to obtain a synthetic feedstock; and

(c) recovering synthetic feedstock.

The pour point depressant is used to lower the temperature of the pour point of the synthetic feedstocks derived from plastics during recovery, transport, storage or use of the synthetic feedstocks.

BRIEF DESCRIPTION OF DRAWINGS

FIG. 1 is a schematic representation of an embodiment of a plastic pyrolysis process.

FIG. 2 is a schematic representation of an embodiment of a plastic pyrolysis process.

DETAILED DESCRIPTION

Although the present disclosure provides references to various embodiments, persons skilled in the art will recognize that changes may be made in form and detail without departing from the spirit and scope of the application. Various embodiments will be described in detail with reference to the figures. Reference to various embodiments does not limit the scope of the claims attached hereto. Additionally, any examples set forth in this application are not intended to be limiting and merely set forth some of the many possible embodiments for the appended claims.

Unless otherwise defined, all technical and scientific terms used herein have the same meaning as commonly understood by one of ordinary skill in the art. In case of conflict, the present document, including definitions, will control. Methods and materials are described below, although methods and materials similar or equivalent to those described herein can be used in practice or testing of the present application. All publications, patent applications, patents and other references mentioned herein are incorporated by reference in their entirety.

The terms “copolymer”, “copolymerize” include not only polymers comprising two monomer residues and polymerization of two different monomers together respectively, but also includes copolymers comprising more than two monomer residues and polymerizing together more than two or more other monomers. Therefore, the term copolymer, for example, includes terpolymer; quadrupolymer; and polymers made from more than four different monomers, and/or polymers comprising, consisting of, or consisting essentially of two different monomer residues.

The term “pour point” is the lowest temperature at which a liquid will pour or flow under a specific set of conditions. Exemplary pour point standards include ASTM D97-11, D585311, and D5949-10.

The term "pour point depressants" or "PPDs" are polymers that reduce or inhibit wax crystal formation in feedstocks such as feedstocks derived from plastic, resulting in lower pour point and improved low or cold temperature flow performance.

The term "synthetic feedstock" refers to hydrocarbons obtained from treatment or processes on plastics. For example, the plastic can be thermally converted to e.g., pyrolysis oil or pyrolysate.

As used herein, the terms "comprise(s)," "include(s)," "having," "has," "can," "contain(s)," and variants thereof are intended to be open-ended transitional phrases, terms, or words that do not preclude the possibility of additional acts or structures. The singular forms "a," "and" and "the" include plural references unless the context clearly dictates otherwise. The present disclosure also contemplates other embodiments "comprising," "consisting of" and "consisting essentially of," the embodiments or elements presented herein, whether explicitly set forth or not.

As used herein, the term "optional" or "optionally" means that the subsequently described event or circumstance may but need not occur, and that the description includes instances where the event or circumstance occurs and instances in which it does not.

As used herein, the term "about" modifying, for example, the quantity of an ingredient in a composition, concentration, volume, process temperature, process time, yield, flow rate, pressure, and like values, and ranges thereof, employed in describing the embodiments of the disclosure, refers to variation in the numerical quantity that can occur, for example, through typical measuring and handling procedures used for making compounds, compositions, concentrates or use formulations; through inadvertent error in these procedures; through differences in the manufacture, source, or purity of starting materials or ingredients used to carry out the methods, and like proximate considerations. The term "about" also encompasses amounts that differ due to aging of a formulation with a particular initial concentration or mixture, and amounts that differ due to mixing or processing a formulation with a particular initial concentration or mixture. Where modified by the term "about" the claims appended hereto include equivalents to these quantities. Further, where "about" is employed to describe a range of values, for example "about 1 to 5" the recitation means "1 to 5" and "about 1 to about 5" and "1 to about 5" and "about 1 to 5" unless specifically limited by context.

As used herein, the term "substantially" means "consisting essentially of" and includes "consisting of." "Consisting essentially of" and "consisting of" are construed as in U.S. patent law. For example, a solution that is "substantially free" of a specified compound or material may be free of that compound or material, or may have a minor amount of that compound or material present, such as through unintended contamination, side reactions, or incomplete purification. A "minor amount" may be a trace, an unmeasurable amount, an amount that does not interfere with a value or property, or some other amount as provided in context. A composition that has "substantially only" a provided list of components may consist of only those components, or have a trace amount of some other component present, or have one or more additional components that do not materially affect the properties of the composition. Additionally, "substantially" modifying, for example, the type or quantity of an ingredient in a composition, a property, a measurable quantity, a method, a value, or a range, employed in describing the embodiments of the disclosure, refers to a variation that does not affect the overall recited composition, property, quantity,

method, value, or range thereof in a manner that negates an intended composition, property, quantity, method, value, or range. Where modified by the term "substantially" the claims appended hereto include equivalents according to this definition.

As used herein, any recited ranges of values contemplate all values within the range and are to be construed as support for claims reciting any sub-ranges having endpoints which are real number values within the recited range. By way of example, a disclosure in this specification of a range of from 1 to 5 shall be considered to support claims to any of the following ranges: 1-5; 1-4; 1-3; 1-2; 2-5; 2-4; 2-3; 3-5; 3-4; and 4-5.

Described are compositions and methods that improve the cold flow properties of synthetic feedstocks from plastics. The cold flow properties can be improved by additives that prevent the formation of wax-like structures and lower the temperature at which the synthetic feedstock solidifies. This addition in turn ensures uninterrupted flow of the synthetic feedstock. Such additives are referred to as pour point depressants or flow improvers.

Several processes are known in which plastic (e.g., waste plastic) is converted to lower molecular weight hydrocarbon materials particularly to hydrocarbon fuel materials. For example, see U.S. Pat. Nos. 6,150,577; 9,200,207; and 9,624,439; each of these publications incorporated herein by reference in their entireties.

Such processes broadly described include breaking the long-chain plastic polymers by pyrolysis-high heat (e.g., from 400° C.-850° C.) with limited or no oxygen and above atmospheric pressure. The resultant pyrolysis effluent is distilled and then condensed. As shown in FIG. 1, an embodiment of a pyrolysis process includes a feeder 12 of waste plastic, a reactor 14, and a condenser system 18. Polymer-containing material is fed through inlet 10 in the feeder, and heat is applied to reactor 14. An outlet 20 from condenser system 18 allows for the product to exit.

The thermal cracking reactors to accomplish this pyrolysis reaction have been described in detail in a number of patents, e.g., U.S. Pat. Nos. 9,624,439; 10,131,847; 10,208,253; and PCT International Pat. Appl. Pub. No. WO 2013/123377A1, each of these publications incorporated herein by reference in their entireties.

In some embodiments, the method of obtaining the synthetic feedstock comprises:

- heating plastic under substantially oxygen free conditions at a temperature of from about 400° C. to about 850° C. to produce a pyrolysis effluent;
- condensing the heated a pyrolysis effluent to obtain a synthetic feedstock;
- recovering synthetic feedstock

In some embodiments, the method of obtaining the synthetic feedstock is in the presence or absence of catalysts.

The pyrolysis reaction produces a range of hydrocarbon products from gases (at temperatures from 10° C. to 50° C. and 0.5-1.5 atmospheric pressure and having 5 carbons or less); modest boiling point liquids (like gasoline (40-200° C.) or diesel fuel 180-360° C.); a higher (e.g., at 250-475° C.) boiling point liquid (oils and waxes), and some solid residues, commonly referred to as char. Char is the material that is left once the pyrolytic process is complete and the fuel recovered. Char contains the additives and contaminants that enter the system as part of the feedstock. The char can be a powdery residue or substance that is more like sludge with a heavy oil component. Glass, metal, calcium carbonate/oxide, clay and carbon black are just a few of the contami-

nants and additives that will remain after the conversion process is complete and become part of the char.

Various plastic types such a thermoplastic and thermoset waste plastics can be used in the above-described process. The types of plastics commonly encountered in waste-plastic feedstock include, without limitation, low-density polyethylene, high-density polyethylene, polypropylene, polystyrene, nylons, and the like, and combinations thereof.

In some embodiments, the pyrolysis reaction (e.g., pyrolysis effluent) results in 2-30% gas (C1-C4 hydrocarbon); (2) 10-50% oil (C5-C15 hydrocarbon); (3) 10-40% waxes ($\geq$ C16 hydrocarbon); and (4) 1-5% char and tar. After completion of the pyrolysis process, the pyrolysis or pyrolysis oil can range from 20-85% oils (C5-C15) and 15-95% waxes ($\geq$ C16) or from 35-80% oils (C5-C15) and 20-65% waxes ($\geq$ C16).

The hydrocarbons that derive from the pyrolysis of waste plastic are a mixture of alkanes, alkenes, olefins and diolefins; the olefin group is generally between C1 and C2, i.e. alpha-olefin, but some alk-2-ene is also produced, the diene is generally in the alpha and omega position, i.e. alk- α,ω -diene; or the dienes are conjugated dienes. In some embodiments, the pyrolysis of plastic produces paraffin compounds, isoparaffins, olefins, diolefins, naphthenes and aromatics.

In some embodiments, the percentage of 1-olefins in the pyrolysis effluent is from 25 to 75% wt; from 40-60 wt %. Pyrolysis conditions include a temperature from about 400-850° C., from about 500-700° C., or from about 600-700° C.

Depending on the processing conditions synthetic feedstock having characteristics similar to crude oil from petroleum sources but can have ash and wax of different ranges. In some embodiments, the synthetic feedstock derived from waste plastic contains waxy hydrocarbons from C16-C36; C16-C20; C21-C29; or C30-C36. In other embodiments, the synthetic feedstock derived from waste plastic contains waxy hydrocarbons with the C16-C20 fraction representing 50-60% of the wax molecules, the C21-C29 fraction being about 40-50% of the waxy molecules and C30+ fraction being less than 2% of the wax fraction; the waxy fraction is about 10-20% of the recovered synthetic feedstock fraction. In still other embodiments, the synthetic feedstocks have 15-20 wt % C9-C16; 75-87% C16-C29; 2-5% C30+, where the carbon chains are predominantly a mixture of alkanes, alkenes and diolefins. In other embodiments, the synthetic feedstocks have 10 wt %<C12, 25 wt % C12-C20, 30 wt % C21-C40 and 35 wt %>C41, where the carbon chains are predominantly a mixture of alkanes, alkenes and diolefins.

Unlike the synthetic feedstock derived from plastics, conventional crude oil that suffers from pour point issues has a broad range of hydrocarbon species where the non-waxy components may help offset some of the waxy nature of these troublesome crude oils. In a conventional waxy crude oil, the waxy components range from C16 to C80+. In one example of a crude, the waxy molecules with a carbon chain range of C22-C40, display a roughly Gaussian distribution and the majority of the waxy molecules were in the C28-C36 range. In another example of a crude, the waxy carbon chain length ranged from C15 to C110, the distribution can be bimodal with the majority of the waxy molecules being in the C24 to C28 or C36 to C52 range.

While there are known dewaxing methods for reducing waxy feeds, either by solvent removal or catalytic dewaxing or isomerization, most of these processes are expensive. Disclosed herein are pour point depressants that lower pour points of synthetic feedstocks derived from plastics (e.g., waste plastic).

In some embodiments, the synthetic feedstock composition has waxy constituents which can precipitate from the synthetic feedstock composition at a temperature greater than its desired or intended storage, transport, or use temperature. In some embodiments, the synthetic feedstock composition can have a wax content greater than 1 weight percent; greater than 5 weight percent; or greater than 10 weight percent. In some embodiments the wax content in the synthetic feedstocks is, 5-95 weight percent; 15-95 weight percent; 20-65 weight percent; 5-40 weight percent; 5-30 weight percent; from 10-25 weight percent; 15-20 weight percent; 10-20 weight percent; or 10-30 weight percent.

In some embodiments, the compounds used in the compositions and methods for lowering or depressing the pour points of synthetic feedstock are polymers (e.g., synthetic). In some embodiments, the polymers are vinyl carboxylic acid ester polymers. In some embodiments the pour point depressants are polymers such as ethylene vinyl acetate, vinyl acetate-acrylate copolymers, alpha olefin maleic anhydride polymers or combinations thereof.

In some embodiments, the pour depressant is a copolymer of ethylene. In some embodiments the copolymer of ethylene is with at least one ethylenically unsaturated monomer, wherein the ethylenically unsaturated monomer is a vinyl carboxylic acid ester.

In some embodiments, vinyl carboxylic esters are, the vinyl esters of carboxylic acids having 2 to 20 carbon atoms, the hydrocarbon radical of which may be linear or branched. Among the carboxylic acids with a branched hydrocarbon radical, some are those whose branching is in the α -position to the carboxyl group, the α -carbon atom being particularly preferably tertiary, i.e., the carboxylic acid being a so-called neocarboxylic acid. In some embodiments, the hydrocarbon radical of the carboxylic acid is linear.

Examples of suitable vinyl carboxylic esters are vinyl acetate, vinyl propionate, vinyl butyrate, vinyl neopentanoate, vinyl hexanoate, vinyl neononanoate, vinyl neodecanoate. In other embodiments the ethylene copolymer is acrylonitrile, or alpha-olefins such as octane, butane, propylene, comb polymers with alkyl side chains such as methacrylate ester copolymers, maleic-olefinic ester copolymers, and maleic-olefinic amide copolymers; and branched copolymers having alkyl side chains such as alkylphenol-formaldehyde copolymers and polyethyleneimines and the like. In some embodiments, the pour point depressant is an ethylene vinyl acetate copolymer.

Also suitable are copolymers which contain two or more mutually different alkenyl carboxylic acid esters in copolymerized form, these differing in the alkenyl function or in the carboxylic acid group. Also suitable are copolymers which, in addition to the alkenyl carboxylic ester(s), contain at least one olefin or at least one (meth) acrylic acid ester in copolymerized form.

Suitable olefins are, for example, those having 3 to 10 carbon atoms and having 1 to 3, 1 or 2, or having one carbon-carbon double bond. In the latter case, the carbon-carbon double bond can be arranged both terminally (α -olefin), internally, or both. In some embodiments the α -olefins have 3 to 6 carbon atoms, such as propene, 1-butene, 1-pentene and 1-hexene.

Suitable (meth) acrylic esters are, for example, esters of (meth) acrylic acid with C1-C 10-alkanols, in particular with methanol, ethanol, propanol, isopropanol, n-butanol, sec-butanol, isobutanol, tert-butanol, pentanol, hexanol, Heptanol, octanol, 2-ethylhexanol, nonanol and decanol.

In some embodiments the vinyl acetate in the ethylene vinyl acetate copolymer is from 5-60 wt % of the total

copolymer; or from 10 to 25 wt %; from 10 to 20 wt %; from 10 to 50 wt %; from 25 to 40 wt %; from 25 to 50 wt %; or from 15 to 25 wt %.

In some embodiments, the copolymer has a molecular weight from 800 to 13,000 g/mol; from 900 to 12,000 g/mol; or from 900-10,000 g/mol. In some embodiments, the molecular weight can be determined by gel permeation chromatography (GPC).

In some embodiments, the ethylene vinyl acetate copolymers used as pour point depressants on synthetic feed stock derived from plastics are present with or without a synergist. In some embodiments the synergist is alpha olefin maleic anhydride. In still other embodiments, the ethylene vinyl acetate is about 900-12,000 molecular weight provided with a solvent and having 10-50 percent vinyl acetate content and 20-70 percent actives.

In some embodiments the copolymers are at least one ethylenically unsaturated monomer, wherein the ethylenically unsaturated monomer is a vinyl carboxylic acid ester.

In some embodiments, vinyl carboxylic esters are, the vinyl esters of carboxylic acids having 2 to 20 carbon atoms, the hydrocarbon radical of which may be linear or branched. Among the carboxylic acids with a branched hydrocarbon radical, some are those whose branching is in the α -position to the carboxyl group, the α -carbon atom being particularly tertiary, i.e., the carboxylic acid being a so-called neocarboxylic acid. In some embodiments, the hydrocarbon radical of the carboxylic acid is linear.

Examples of suitable vinyl carboxylic esters are vinyl acetate, vinyl propionate, vinyl butyrate, vinyl neopentanoate, vinyl hexanoate, vinyl neononanoate, vinyl neodecanoate. In some embodiments, the vinyl carboxylic ester is copolymerized with an acrylate.

In some embodiments the acrylates are acrylate esters. In some embodiments, the acrylate esters are of C1-C20-alkanols, such as methyl acrylate, ethyl acrylate, propyl acrylate, isopropyl acrylate, n-butyl acrylate, isobutyl acrylate, tert-butyl acrylate, n-pentyl acrylate, neopentyl acrylate, hexyl acrylate, heptyl acrylate, octyl acrylate, neooctyl acrylate, 2-ethylhexyl acrylate, nonyl acrylate, neonyl acrylate, decyl acrylate, neodecyl acrylate, lauryl acrylate, palmityl acrylate and stearyl acrylate; also the corresponding methacrylic, crotonic and isocrotonic esters are used.

In some embodiments, the pour point depressant is a vinyl acetate-acrylate copolymer.

In some embodiments the vinyl acetate in the vinyl acetate-acrylate copolymer is from 5-30 wt % of the total copolymer; from 8-20 wt %; 10 to 25 wt %; or from 10 to 20 wt %.

In some embodiments, the copolymer has a molecular weight from 800 to 13,000 g/mol; from 900 to 12,000 g/mol; or from 900-10,000 g/mol; or from 900-9300 g/mol. In some embodiments, the molecular weight can be determined by gel permeation chromatography (GPC).

In some embodiments, the vinyl acetate-acrylate copolymers are used as pour point depressants on synthetic feed stock derived from plastics. In some embodiments the vinyl acetate-acrylate is about 900-12,000 molecular weight provided with a solvent and having 8-20 percent vinyl acetate content and 20-70 percent actives.

In some embodiments, the pour depressant is a copolymer of an alpha-olefin monomer with an ethylenically unsaturated carboxylic acid monomer or derivatives thereof such as fumaric acid, maleic anhydride, maleic acid, (meth) acrylic acid, itaconic anhydride or itaconic acid, maleimide and N-alkyl, N-aryl, and N-alkaryl maleimides, substituted moiety such as citraconic anhydride, citraconimide and

N-alkyl, N-aryl, and N-alkaryl citraconimides or combinations thereof. In some embodiments, the ethylenically unsaturated carboxylic acid or derivatives thereof may be an acid or anhydride or derivatives thereof. In some embodiments, the ethylenically unsaturated carboxylic acid monomer is maleic anhydride monomer having the formula (I):

(I)

wherein R₅ and R₆ are independently selected from hydrogen or C1-C30 alkyl. In some embodiments, the maleic anhydride residue is further reacted with about 0.01 to 2.0 equivalents of a C12-C60 alkanol or amine per equivalent of anhydride.

In some embodiments, the one or more alpha olefin monomers having the formula (II):

(II)

wherein R₁, R₂, R₃, and R₄ are independently selected from hydrogen and C5-C40 alkyl.

In some embodiments, the alpha olefin contains from 15-40 carbon atoms or 18-36 or 20-35 carbon atoms.

In some embodiments, the olefin is linear and/or contains linear hydrocarbon chains such as alkyl or alkaryl chains attached to the double bond, then polymers of the olefin including copolymers of the olefin have pendant side chains. For example, polymers of linear alpha olefins having 14 carbon atoms or more, when polymerized and/or copolymerized, impart linear side chains of 12 carbon atoms or more to the resulting polymer. Long-chain alkenes, wherein the double bond is not in the 1-position, are also suitable because when polymerized the resulting polymer of the alkene monomer has linear side chains of at least 12 carbon atoms. Polymers of long chain alkenes with 12 carbon atoms or more on one side of the double bond and 12 carbon atoms or more on the opposing side of the double bond, when polymerized and/or copolymerized, form brush polymers. Such brush polymers have sets of opposing pendant side chains. Both brush and comb polymers are both useful in the disclosed embodiments.

In some embodiments, the pour point depressant is an alpha olefin-maleic anhydride copolymer (OMAC). In some embodiments, the copolymer of formula (I) and formula (II) is further reacted via the maleic anhydride residue with one or more alkanol or amine compounds to form the corresponding carboxylate or amide functionalities. In some such embodiments, the maleic anhydride residue is reacted with about 0.5 to 2.0 equivalents of the alkanol or amine per equivalent of anhydride. The alkanol or amine compounds are linear, branched, aromatic, or alkylaromatic compounds having about 12 to 60 carbons.

In some embodiments the alpha-olefin maleic anhydride copolymer is from 10,00-70,000 g/mol; 10,00-55,000 g/mol; 20,00-50,000 g/mol; 20,00-70,000 g/mol or from 15,000-

35,000 g/mol. In some embodiments, the molecular weight can be determined by gel permeation chromatography (GPC).

In some embodiments, the alpha-olefin maleic anhydride copolymer used as pour point depressants on synthetic feed stock derived from plastics is about 20,00-70,000 g/mol molecular weight provided with a solvent and having 20-90 percent actives.

Preparation of pour point depressant polymers may be made by any method known in the art such as by solution polymerization of free radical initiation or high-pressure polymerizations that may be carried out in an autoclave or suitable reactor. For example, preparation of alpha-olefin with an ethylenically unsaturated carboxylic acid (e.g., alpha-olefin maleic anhydride copolymers are known in the art. For example, see U.S. Pat. No. 5,441,545, which is incorporated herein by reference.

In some embodiments, the pour point depressant is formulated with solvents such as water, alcohols, aromatics, naphthenic, aliphatic and non-polymeric ester compounds (as disclosed in U.S. application Ser. No. 15/399,025 (U.S. Pat. Appl. Pub. No 2017/0190949, which is incorporated herein by reference in its entirety) and combinations thereof. In some embodiments, the solvents are heavy aromatic naphtha or light aromatic naphtha solvents.

In some embodiments the solvents are 10 wt % to 99 wt % of the pour point depressant; 10-25 wt %; 20-50 wt %; 30-75 wt %; 50-75%; 75-100 wt % of the pour point depressant.

In some embodiments, the pour point depressants are 20-99% active; 50-75%; 60-70%; 75-99% active; 20-90%; 20-70%; 30-70%; 20-50%; or 20-30% active.

In some embodiments, the pour point depressants are provided neat (viz., without a solvent). In some embodiments, the pour point depressants are provided as a concentrate. In some embodiments the pour point depressant concentrates have 1 wt % to 20 wt % pour point depressant (PPD), or about 3 wt % to 20 wt %, or about 5 wt % to 20 wt %, or about 7 wt % to 20 wt %, or about 10 wt % to 20 wt % PPD.

In some embodiments, the pour point depressant can include one or more additional components such other pour point depressants, paraffin inhibitors, asphaltene dispersants, wax dispersants, tar dispersants, neutralizers (e.g., amine neutralizers), surfactants, biocides, preservatives, stabilizers and the like or any combination thereof.

Wax dispersants can stabilize paraffin crystals which have formed and prevent them from sedimenting. The wax dispersants used may be, for example, alkylphenols, alkylphenol-formaldehyde resins or dodecylbenzenesulfonic acid.

The method of applying the pour point depressant to the synthetic feedstock is not particularly limited. One of skill will appreciate that the synthetic feedstock additives such as the pour point depressant are conventionally added by using available equipment including e.g., pipes, mixers, pumps, tanks, injection ports, and the like.

In some embodiments, the pour point depressant is added into a synthetic feedstock obtained from plastics. In some embodiments, the pour point depressant is an ethylene vinyl acetate copolymer. In other embodiments, the pour point depressant is added to a synthetic feedstock that contains waxes. In still other embodiments, ethylene vinyl acetate copolymer, vinyl acetate-acrylate copolymer, alpha olefin maleic anhydride copolymer or combinations thereof are added to a synthetic feedstock that contains waxes, char and tar. In some embodiments, the ethylene vinyl acetate copolymer, vinyl acetate-acrylate copolymer, alpha olefin maleic

anhydride copolymer or combinations thereof are added to a synthetic feedstock that contains waxes having C16-C36. In some embodiments, the ethylene vinyl acetate copolymer, vinyl acetate-acrylate copolymer, alpha olefin maleic anhydride copolymer or combinations thereof are suitable pour points for synthetic feedstock having from 20-85% oils (C5-C15) and 15-95% waxes ($\geq$ C16); or from 35-80% oils (C5-C15) and 20-65% waxes ($\geq$ C16); or 15-20 wt % C9-C16; 75-87% C16-C29; 2-5% C30+, where the carbon chains are predominantly a mixture of alkanes, alkenes and diolefins. In still other embodiments, the ethylene vinyl acetate copolymer, vinyl acetate-acrylate copolymer, alpha olefin maleic anhydride copolymer or combinations thereof are suitable pour points for synthetic feedstock having 10 wt % $<$ C12, 25 wt % C12-C20, 30 wt % C21-C40 and 35 wt % $>$ C41, where the carbon chains are predominantly a mixture of alkanes, alkenes and diolefins.

While an effective amount of the pour point depressant used depends on a number of factors such as the local operating conditions, the type of synthetic feedstock obtained from the plastic type processed, the temperature and other characteristics of the process, in some embodiments, the pour point depressant is used from 50 ppm to 10,000 ppm; 50 ppm to 5,000 ppm; 550 ppm to 5,000 ppm; 250 ppm to 1000 ppm; 50 ppm to 1,000 ppm; 150 to 450 ppm; 50 ppm to 500 ppm in the synthetic feedstock.

Flow properties of the synthetic feedstock can be evaluated by any known method or test. For example, pour points can be measured according to ASTM D97.

In some embodiments the synthetic feedstock with the pour point depressants have pour points (measured under ASTM D97) of less than -24° C., less than -20° C.; less than -10° C., less than -5° C. Such synthetic feedstock continues to flow thereby being allowed to be poured, pumped or transferred at temperatures between, for example -40° C. to 20° C. In some embodiments, the compositions containing the pour point depressants flow, and thus are pourable or pumpable, at temperatures as low as -40° C., or -40° C. to 20° C.; to -40° C., or -5° C. to -40° C., or -10° C. to -40° C., or -15° C. to -40° C., or -20° C. to -40° C., or -25° C. to -40° C., or -30° C. to -40° C.

In some embodiments the pour point depressants reduce the pour points by 3 to 42° C.; 3 to 30° C.; 3 to 20° C.; 10 to 20° C.; by 3° C. to 20° C.; 3° C. to 15° C.; 3° C. to 10° C.; or 3° C. to 5° C.

In some embodiments the pour point depressants at 250-450 ppm reduce the pour points by 3 to 42° C.; 3 to 30° C.; 3 to 20° C.; 10 to 20° C.; by 3° C. to 20° C.; 3° C. to 15° C.; 3° C. to 10° C.; or 3° C. to 5° C.

In some embodiments, the compositions comprise, consist essentially of, or consist of ethylene vinyl acetate copolymer, vinyl acetate-acrylate copolymer, alpha olefin maleic anhydride copolymer or combinations thereof in synthetic feedstock. In such embodiments, the pour points are reduced from 3 to 42° C.; when 50 ppm to 10,000 ppm are added to the synthetic feedstock derived from plastics.

The application is further described below with additional non-limiting embodiments:

1. A method of improving the cold flow properties of a plastic-derived synthetic feedstock composition comprising:
adding a pour point depressant to a plastic-derived synthetic feedstock composition.
2. The method of embodiment 1, wherein the synthetic feedstock composition further comprises other pour point dispersants, paraffin inhibitors, asphaltene disper-

11

- sants, wax dispersants, tar dispersants, neutralizers, surfactants, biocides, preservatives, stabilizers or any combination thereof.
3. The method as in one of embodiments 1-2, wherein the synthetic feedstock comprises from 20-85% oils (C5-C15) and 15-95% waxes ($\geq$ C16); or from 35-80% oils (C5-C15) and 20-65% waxes ($\geq$ C16). 5
  4. The method as in one of embodiments 1-3, wherein the waxes comprise C16-C36.
  5. The method as in one of embodiments 1-4, wherein the pour point depressant is a polymer.
  6. The method as in one of embodiments 1-5, wherein the pour point depressant is a synthetic polymer.
  7. The method as in one of embodiments 1-6 wherein the polymer comprises a vinyl carboxylate. 15
  8. The method as in one of embodiments 1-7, wherein the pour point depressant is an ethylene vinyl acetate copolymer or a vinyl acetate-acrylate copolymer or combinations thereof.
  9. The method as in one of embodiments 1-8, wherein the pour point depressant is an alpha olefin maleic anhydride.
  10. The method as in one of embodiments 1-9, wherein the pour point depressant is added to the synthetic feedstock composition from about 50 ppm to 5000 ppm. 25
  11. The method as in one of embodiments 1-10, wherein the pour point depressant lowers the pour point of the synthetic feedstock composition by 3° C. to 42° C. 30
  12. The method as in one of embodiments 1-11, wherein the synthetic feedstock composition comprises a pour point depressant has a pour point less than -24° C.
  13. A method of obtaining the synthetic feedstock comprising:
    - (a) heating plastic under substantially oxygen free conditions at a temperature of from about 400° C. to about 850° C. to produce a pyrolysis effluent;
    - (b) condensing the heated a pyrolysis effluent to obtain a synthetic feedstock; (c) recovering synthetic feedstock; and
    - (d) adding a pour point depressant to the synthetic feedstock to lower the pour point. 35
  14. The method of embodiment 13, wherein the plastic comprises waste plastic.
  - 45
  15. The method as in one of embodiments 13-14, wherein the heating is in the presence or absence of a catalyst.
  16. The method as in one of embodiments 13-15, wherein the plastic comprises polyethylene, polypropylene, polyvinylchloride, polystyrene, polyethylene terephthalate and combinations thereof. 50
  17. The method as in one of embodiments 13-16, wherein the synthetic feedstock comprises from 20-85% oils (C5-C15) and 15-95% waxes ($\geq$ C16); or from 35-80% oils (C5-C15) and 20-65% waxes ($\geq$ C16). 55
  18. The method as in one of embodiments 13-17, wherein the waxes comprise C16-C36.
  19. The method as in one of embodiments 13-18, wherein the pour point depressant is a polymer.
  20. The method as in one of embodiments 13-19, wherein the pour point depressant is a synthetic polymer. 60
  21. The method as in one of embodiments 13-20, wherein the polymer comprises a vinyl carboxylate.
  22. The method as in one of embodiments 13-21, wherein the pour point depressant is an ethylene vinyl acetate copolymer or a vinyl acetate-acrylate copolymer or combinations thereof. 65

12

23. The method as in one of embodiments 13-22, wherein the pour point depressant is an alpha olefin maleic anhydride.
24. The method as in one of embodiments 13-23, wherein the pour point depressant is an ethylene vinyl acetate copolymer.
25. The method as in one of embodiments 13-24, wherein the pour point depressant is added to the synthetic feedstock from about 50 ppm to 5000 ppm.
26. The method as in one of embodiments 13-25, wherein the pour point depressant lowers the pour point of the synthetic feedstock by 3° C. to 42° C.
27. The method as in one of embodiments 13-26, wherein the synthetic feedstock comprising a pour point depressant has a pour point less than -24° C.
28. A composition comprising a synthetic feedstock derived from plastic and a pour point depressant.
29. The composition of embodiment 27, wherein the synthetic feedstock comprises from 20-85% oils (C5-C15) and 15-95% waxes ($\geq$ C16); or from 35-80% oils (C5-C15) and 20-65% waxes ($\geq$ C16).
30. The composition as in one of embodiments 27-28, wherein the waxes comprise C16-C36.
31. The composition as in one of embodiments 27-29, wherein the pour point depressant comprises a polymer.
32. The composition as in one of embodiments 27-30, wherein the pour point depressant comprises a synthetic polymer.
33. The composition as in one of embodiments 27-31, wherein the pour point depressant comprises a vinyl carboxylate.
34. The composition as in one of embodiments 27-32, wherein the pour point depressant is an ethylene vinyl acetate copolymer or a vinyl acetate-acrylate copolymer or combinations thereof.
35. The composition as in one of embodiments 27-33, wherein the pour point depressant is an alpha olefin maleic anhydride.
36. The composition as in one of embodiments 27-34, wherein the pour point depressant is added to the synthetic feedstock from about 50 ppm to 5000 ppm.
37. The composition as in one of embodiments 27-35, wherein the pour point depressant lowers the pour point of the synthetic feedstock by 3° C. to 42° C.
38. The composition as in one of embodiments 27-36, wherein the synthetic feedstock comprising a pour point depressant has a pour point less than -24° C.
39. A composition comprising a pour point depressant and a synthetic feedstock, wherein the pour point depressant is a polymer added to the synthetic feedstock, the synthetic feedstock is provided by the method comprising:
  - (a) heating plastic under substantially oxygen free conditions at a temperature of from about 400° C. to about 850° C. to produce a pyrolysis effluent;
  - (b) condensing the heated a pyrolysis effluent to obtain a synthetic feedstock; and
  - (c) recovering synthetic feedstock. 55
40. The composition of embodiment 38, wherein the synthetic feedstock comprises from 20-85% oils (C5-C15) and 15-95% waxes ($\geq$ C16); or from 35-80% oils (C5-C15) and 20-65% waxes ($\geq$ C16).
41. The composition as in one of embodiments 38-39, wherein the waxes comprise C16-C36.
42. The composition as in one of embodiments 38-40, wherein the pour point depressant comprises a polymer. 60

13

43. The composition as in one of embodiments 38-41, wherein the pour point depressant comprises a synthetic polymer.
44. The composition as in one of embodiments 38-42, wherein the pour point depressant comprises a vinyl carboxylate.
45. The composition as in one of embodiments 38-43, wherein the pour point depressant comprises an ethylene vinyl acetate copolymer or a vinyl acetate-acrylate copolymer or combinations thereof.
46. The composition as in one of embodiments 38-44, wherein the pour point depressant comprises an alpha olefin maleic anhydride.
47. The composition as in one of embodiments 38-45, wherein the pour point depressant is added to the synthetic feedstock from about 50 ppm to 5000 ppm.
48. The composition as in one of embodiments 38-46, wherein the pour point depressant lowers the pour point of the synthetic feedstock by 3° C. to 42° C.
49. The composition as in one of embodiments 38-47, wherein the synthetic feedstock comprising a pour point depressant has a pour point less than -24° C.
50. Use of the pour point depressants as in one of embodiments 1-48 to lower the pour point of synthetic feedstocks derived from plastics.

EXAMPLES

The following examples are intended to illustrate different aspects and embodiments of the application and are not to be considered limiting the scope. It will be recognized that various modifications and changes may be made without departing from the scope of the application and claims.

Example 1 Cold Flow Additives in Synthetic Feedstock Derived from Plastic

The pour points of synthetic feedstock derived from plastic with various pour point depressants were determined according to ASTM D97. The synthetic feedstocks having the following carbon chains were used: Sample 1: 15-20 wt % C9-C16; 75-87% C16-C29; 2-5% C30+, where the carbon chains are predominantly a mixture of alkanes, alkenes and diolefins; and Sample 2 10 wt %<C₁₂, 25 wt % C₁₂-C₂₀, 30 wt % C₂₁-C₄₀ and 35 wt %>C₄₁.

The chemistries of the various pour point depressants used are shown below in Table 1:

TABLE 1

Category No.	Chemistry-type	MW range (by GPC)	Vinyl acetate content	Active Content
1	ethylene-vinyl acetate copolymer	900-12,000 g/mol	10-50%	20-70%
2	ethylene-vinyl acetate copolymer with alpha-olefin maleic anhydride-based synergist	900-12,000 g/mol	10-50%	20-70%

14

TABLE 1-continued

Category No.	Chemistry-type	MW range (by GPC)	Vinyl acetate content	Active Content
5	3	alpha-olefin-maleic anhydride-based copolymer (C18-C36)	20,00-70,000 g/mol	NA
	4	vinyl acetate-acrylate copolymer	900-9,300	8-20% 30-70%

Table 2 shows the different categories of pour point depressants tested at varying dosages in Sample 1.

Table 3 showed that while all categories of pour point depressants tested in Sample 2 showed promising pour point depression, alpha-olefin-maleic anhydride-based copolymers and vinyl acetate-acrylate copolymers were the most effective at lower dosage ranges.

What is claimed is:

1. A method of obtaining a synthetic feedstock, comprising:
  - (a) heating plastic under substantially oxygen free conditions at a temperature of from about 400° C. to about 850° C. to produce a pyrolysis effluent;
  - (b) condensing the heated pyrolysis effluent to obtain a synthetic feedstock;
  - (c) recovering the synthetic feedstock; and
  - (d) adding a pour point depressant to the synthetic feedstock to lower the pour point, wherein the pour point depressant comprises an ethylene vinyl acetate copolymer and an alpha olefin maleic anhydride polymer.
2. The method of claim 1, wherein the plastic comprises waste plastic.

16

3. The method of claim 1, wherein the heating is in the presence or absence of a catalyst.

4. The method of claim 1, wherein the plastic comprises polyethylene, polypropylene, polyvinylchloride, polystyrene, polyethylene terephthalate, or a combination thereof.

5. The method of claim 1, wherein the synthetic feedstock comprises from about 20 wt. % to about 85 wt. % of an oil (C₅-C₁₅) and about 15 wt. % to about 95 wt. % of a wax (≥ C₁₆).

10 6. The method of claim 5, wherein the wax comprises a compound having from about 16 carbon atoms to about 36 carbon atoms.

15 7. The method of claim 1, wherein the synthetic feedstock comprises from about 35 wt. % to about 80 wt. % of an oil (C₅-C₁₅) and about 20 wt. % to about 65 wt. % of a wax (>C₁₆).

8. The method of claim 1, further comprising adding from about 50 ppm to about 5,000 ppm of the pour point depressant to the synthetic feedstock.

9. The method of claim 1, wherein the ethylene vinyl 20 acetate copolymer has a weight average molecular weight ranging from about 900 g/mol to about 12,000 g/mol and a vinyl acetate content ranging from about 10 mol % to about 50 mol %.

25 10. The method of claim 1, wherein the alpha olefin maleic anhydride polymer has a weight average molecular weight ranging from about 20,000 g/mol to about 70,000 g/mol.

30 11. The method of claim 1, wherein the pour point depressant lowers the pour point of the synthetic feedstock by about 3° C. to about 42° C.

12. The method of claim 1, wherein the synthetic feedstock comprising the pour point depressant has a pour point less than about -5° C.

* * * * *
